ARTICULATED LOG SKIDDER HAVING A TELESCOPIC BOOM FOR THROWING OUT THE IN-HAUL CABLE

Albert R. Wirkkala, Naselle, Wash.
Filed Aug. 23, 1965, Ser. No. 481,805
3 Claims. (Cl. 212—7)

This invention relates to logging vehicles of those kinds employed for the pick-up and conveyance of logs from the forests or woods, involving the use of a boom, choker hooks, grapples or tongs as attached to a haul-in cable leading from a powered winch drum.

It being a principal object of the present invention to provide a logging vehicle of the above stated character and including a telescopically extendable and retractable boom equipped at its extendable end with means whereby the log lifting gear connected to the haul-in line may be cast out, incident to the extension of the telescopic boom from its indrawn position to a position for connection with the load to be pulled in by the haul-in line when the line is wound onto the winch drum.

It is a further object of the invention to provide a vehicle comprising a powered steerable forward section and a rear or trailing section which are joined in an articulated draft connection. The extendable boom is mounted at its ends on and extends between the two sections. One of the two sections also mounts the cable winding winch and fairleader rolls over which the haul-in cable and rigging lines operate for the raising and dragging in of logs or the like.

Further objects and advantages of the invention reside in the specific combination of parts and in their mode of use as will hereinafter be fully described.

In accomplishing the above mentioned and other objects of the invention, I have provided the improved details of construction, the preferred forms of which are illustrated in the accompanying drawings, wherein:

FIG. 1 is a side view of the vehicle of the present invention as equipped with a telescopically extendable boom for pulling out the log pick-up rigging being used therewith.

FIG. 2 is a top or plan view of the vehicle of FIG. 1 with the boom retracted.

FIG. 3 is an enlarged cross-section of the boom and a rotatably mounted supporting collar as applied thereto for its support on the arch unit.

Referring more in detail to the drawings:

The present mobile vehicle is designated in its entirety by reference character T. It is here shown to comprise a forward end section 10 supported on a cross-axle 11 that is equipped at its ends with traction wheels 12—12 and is powered by a suitable engine designated by numeral 13 through conventional transmission gearing operable under control of the vehicle operator.

Pivottally attached to the forward section 10 by a draft connection designated at 15 is the rear end section 16 of the vehicle T. This section is supported by a cross-axle 17 equipped at its ends with paired wheels 12'—12' like those of the forward section 10 and spaced to track therewith. The rear section mounts a transverse arch 20 that is equipped at its top with a four roller fairleader 22. The fairleader guides the haul-in cable 23 that extends therethrough from a powered winch drum 24 here shown to be mounted on the frame of the rear end section 16. The cable 23 is equipped at its outer end with a ring 25, shackle or other suitable means for the securing thereto of choker lines 26 or the like. The choker lines are also secured to the logs for the pulling in of them as the cable 23 is wound onto the winch drum. The winding in of the cable over the fairleader

2

lifts the forward ends of the logs as shown in FIG. 1, preparatory for their being dragged or skidded to a place of deposit.

When the choker lines are disconnected from the log or logs, and the vehicle is returned to the forest for the next load, the choker lines, hooks and cable to which they are attached must be drawn out from the winch drum through the fairlead for application and securing to the next load of logs. This operation is very difficult and time-consuming when done manually. Therefore, to expedite this operation, I have the telescopic boom 28 which accomplishes this task in the following manner:

It has been shown in the drawings that the boom designated by numeral 28 is disposed substantially horizontally on the vehicle. It is supported at its forward and rearward ends respectively in mounting collars 30—30' applied thereabout and mounted for turning on vertical bearing pins 31 as in FIG. 3 on base plates 32 mounted respectively on a frame or roof structure 33 of the forward section 10 of the vehicle. A similar plate 35 is mounted on the arch or rear section 16. The forward end of the boom is clamped in its collar 30 and the rear end of the boom is slidable in its collar 30' to allow for freedom in articulation of the rear section.

The telescopic boom is shown in FIG. 3 to comprise three coaxial tubular sections 36, 37 and 38 and a central extendable piston rod 39. The elements of the boom may be round, square or of other cross-section shapes.

A pressure medium is adapted to be applied to the innermost end of the larger or enclosing cylinder through a tubular line 40 for boom extension. The boom is retracted incident to the winding in of the cable 23. Connected to the outer end of the central rod 39 is a hook 41 which may be detachably applied to the cable ring 25 so that when the boom is extended, the haul-in cable and the connected choker lines attached thereto will be drawn or cast out from the winch drum through the fairleader. Thus the laborious task above mentioned, of manual out-haul, may be easily and readily accomplished to the extent of extension of the boom.

Furthermore, it is to be understood that the mounting of the telescopic boom in the pivotally or rotatably mounted collars permits the articulated maneuverability of the vehicle over rough terrain for side hill logging.

In lieu of the use of choker lines and hooks, tongs or grapples of various kinds may be likewise employed for log pick-up and yarding. Devices of this kind may also be mounted on crawler tractors, motor trucks and the like.

What I claim to be new is:

1. A mobile logging vehicle comprising a powered, steerable forward section and a trailing arch section; said sections being joined by an articulated shaft connection, a telescopically extendable boom supported at its opposite ends, respectively, on the joined sections of said vehicle and having a rearwardly extendable piston rod and means for its extension and retraction, a cable winding drum mounted on said vehicle, a fairleader mounted by said trailing arch section below the rear end of the boom, an inhaul cable wound on said drum and extended rearwardly therefrom over said fairleader, log pick-up means attached to the end of the cable, a connector means attached at one end to the free end of said cable and at its other end to the extendable end of said piston rod whereby said cable may be drawn out from said drum by the extending of the piston rod from the boom and the pick-up means cast rearwardly from the vehicle for log-making log connections.

2. A logging vehicle according to claim 1 wherein said telescopically extendable boom is mounted on and lengthwise of said vehicle and has pivoted supporting bearings

at its ends that permit the articulation of the joined sections; one of said bearings being fixed to the boom to hold it against longitudinal slippage, and the other providing for endwise slippage of the boom therein.

3. A logging vehicle according to claim 2 wherein said boom is mounted on said vehicle sections lengthwise thereof and substantially on a horizontal position to overhang the trailing arch section.
